(57) **CLAIM**

The ornamental design for an electrical connector, as shown and described.

DESCRIPTION

FIG. 1 is a bottom view of the design for an electrical connector;

FIG. 2 is a front view thereof;

FIG. 3 is a front isometric view thereof;

FIG. 4 is a left side view thereof;

FIG. 5 is a rear view thereof;

FIG. 6 is a rear isometric view thereof;

FIG. 7 is a right side view thereof; and,

FIG. 8 is a top view thereof.

Any broken lines in the drawing views are included for the purpose of illustrating portions of the electrical connector that form no part of the claimed design.

1 Claim, 8 Drawing Sheets
